UNITED STATES PATENT OFFICE.

WILLIAM B. FLEMING, OF DETROIT, MICHIGAN.

ELECTROPNEUMATIC ORGAN-ACTION.

SPECIFICATION forming part of Letters Patent No. 666,658, dated January 29, 1901.

Application filed January 15, 1900. Serial No. 1,467. (No model.)

To all whom it may concern:

Be it known that I, WILLIAM B. FLEMING, a citizen of the United States, residing at Detroit, county of Wayne, State of Michigan, have invented a certain new and useful Improvement in Electrical Actions for Pipe-Organs; and I declare the following to be a full, clear, and exact description of the invention, such as will enable others skilled in the art to which it appertains to make and use the same, reference being had to the accompanying drawings, which form a part of this specification.

My invention has for its object certain new and useful improvements in an electrical action for pipe-organs; and it consists of the combination, arrangement, and structure of devices hereinafter described and claimed, and illustrated in the accompanying drawings, in which—

Figure 1 is a diagrammatic view in vertical section and in side elevation embodying my invention. Fig. 2 is a vertical longitudinal section through the key and contact-bar. Fig. 3 is a detail view in perspective of the contact-plate attached to the key. Fig. 4 is a detail view, in inverted perspective, of the contact-finger attached to the contact-bar. Fig. 5 is a view in vertical section through the top board of the wind-chest, showing the electromagnet engaged thereupon and the adjacent pneumatic. Fig. 6 is a detail view of the base of the magnet. Fig. 7 is a detail view of the bed upon which the magnet rests. Fig. 8 is a view in vertical section through the base of the wind-chest A⁴, the chest 12, and adjacent parts.

Certain features shown in the accompanying drawings are embodied in United States Letters Patent issued to me February 20, 1900, No. 643,840.

I carry out my invention as follows:

A fresh-wind box or chest is indicated at A, the top board being indicated at B². The box A, it will be understood, is continuously supplied with air in any suitable manner when the organ is in use. An additional wind-chest is indicated at B, communicating with the chest A, as through a channeled board B'. Communication of the channeled board with the wind-chest A is controlled by valves, (indicated at a and a'). The wind-

chest A is formed with a bottom board C, constructed with a channel C', into which the channeled board B' communicates, the said valves seating in said bottom board, as set forth in the application above referred to. The wind-chest B may be of any desired construction, the same being preferably provided with a pneumatic, (indicated at E.)

F is a chest-bar forming one side of the wind-chest B, said chest-bar being constructed with an exhaust-channel F', opening into the channeled board B' and into the interior of the pneumatic E. This chest-bar is also shown constructed with a channel F², communicating with the wind-chest B and with an adjacent pipe D, the communication of the channel F² with the wind-chest B being governed by the pallet or valve E', forming a part of the pneumatic E. The valve a controls the communication of the channel C' into the interior of the wind-chest A, while the valve a' controls the communication of the channel C' with the atmosphere. The valves a and a' are connected with a valve-rod G, actuated by a pneumatic a³, with which said rod is connected.

The top board of the wind-chest A is constructed with a channel a², communicating into a pneumatic J.

H is an electromagnet, preferably inclosed in a chamber H', the channel a² exhausting through a channel a⁴. A single chamber H' may inclose several magnets. The top board of the wind-chest A is also provided with an additional channel a⁵, communicating with the pneumatic a³, said channel at its opposite end communicating with the wind-chest A and exhausting to the atmosphere, said communication and exhaust being controlled by valves a⁶ and a⁷ upon a stem M. The communication of the channel a² with the channel a⁴ is governed by the armature h of the magnet.

Into the top board B², I prefer to locate a metal bed-plate (indicated at H²) recessed on its upper surface, (shown in detail in Fig. 7,) provided with a central orifice (indicated at h') communicating with the channel a⁴, the armature h seating over said orifice, except when attracted off its seat by the magnet. When the armature is seated, the communication of the channel a² with the chan-

nel a^4 is cut off, and when unseated the communication of said channels is open. The bed-plate H^2 is formed with an opening (indicated at h^2) through which the channel a^2 opens. The magnet H is formed with a base-plate H^3 , (shown in detail in Fig. 6,) the plate H^3 and bed H^2 being provided with registering orifices (indicated at h^3) through which the parts may be screwed down upon the top board B^2 . The center of the bed H^2 is depressed, as shown more particularly in Fig. 5, to set into a corresponding recess in the top board B^2 and is so constructed as to give room for the armature h between the depressed portion of the bed and the under surface of the base-plate. By constructing the magnet with a base-plate in this manner and engaging upon the top board a bed-plate constructed as described it is evident that each of the parts may be made in duplicate, so as to be conveniently and readily assembled.

It will be obvious that when the armature is unseated the pneumatic J will be permitted to exhaust. On the other hand, when the armature is seated the said pneumatic may be inflated, the said pneumatic being preferably provided with a bleed-hole j to aid in supplying the same with air. With the pneumatic J is connected a rod K , connected with a contact-bar Q , which may be provided with one or more contact-pins q .

L indicates a lever connected with the rod K , said lever being actuated by said rod as the pneumatic J is inflated and exhausted. The valve-stem M , carrying the valves a^6 and a^7 , is connected with the lever L , as shown.

M' indicates a spring engaged with the valve-stem M to normally hold the valve a^7 closed and the valve a^6 open.

40 The base-plate H^3 , I construct with orifices h^4 to equalize the pressure within the chest A and the chamber H' about the magnets.

It will be understood that there are as many electromagnets H and pneumatics J and a^3 , with their connected parts, as there are keys on the corresponding keyboard.

N and N' denote electrical conductors arranged to form a circuit through the bar Q .

50 R denotes a rail provided with a metal contact-arm r , projecting into the pathway of the pin q on the bar Q in such a manner that when the bar Q is lifted by the exhaustion of the pneumatic J electrical contacts will be formed with said contact-arm r , thereby completing the circuit through the corresponding conductors N N' , which at corresponding extremities are arranged thus to be brought into contact with the pin q .

55 S represents a key, and T represents a contact-rail provided with a contact-finger t . (Shown in detail in Fig. 4.)

U is a contact-plate attached to the rear end of the key S . This plate is recessed at its inner end, as indicated at U' . The bifurcated ends of the rear end of the plate are connected by a metal cross-piece u^2 , while the contact-finger t is constructed with a rib t' ,

preferably arranged at an angle across the outer end of the finger, as shown in Fig. 4, said cross-piece u^2 arranged to contact with the rib t' when the key is depressed. The contact-plate U may be bolted to the rear end of the key, as shown, and is also preferably provided with a non-conducting strip, as of felt, (indicated at S' ,) upon which the adjacent end of the finger t may normally rest when the key is in normal position. The tilting of the key, however, tilts the cross-piece u^2 against the rib t' , and owing to the angular position of said rib the cross-piece u^2 has a sliding connection therewith, preventing the liability of undue wear or burning out at any given point.

V is a rail located above the rear end of the key, with which is connected a rod V' , upon which the key S is engaged.

V^2 is a spring to restore the key to normal position.

The finger t of the contact-rail T is electrically connected, as by a conductor N^2 , with a battery-strip P , said strip being connected with the magnet H by a conductor N^3 . The magnet is furthermore connected, as by a conductor N^4 , with a junction-plate P' , said junction-plate being connected by a conductor N^5 to a battery N^6 . The rail V is provided with a metal plate V^3 and also with a junction-plate V^4 . The plates V^3 and V^4 are preferably connected by a conductor n , while also the plate V^4 is connected with a conductor n' , leading to the battery N^6 , the conductor N' forming a juncture with the conductor n' , as shown. The contact-plate U is connected with the plate V^3 by a conductor n^2 . The plate V^4 keeps the spring from cutting into the wood, and its employment in connection with the plate U and spring V^2 enables the current also to pass through the spring, while the connection of the plates U and V^3 by the conductor N^2 and the connection of the plates V^3 V^4 with the conductor n affords additional means for the current to pass through the plate U to the plate V^4 . By thus affording a double circuit between the plates U and V^4 I am sure of having a circuit at all times, inasmuch as if the one fails the other will be in readiness to carry the current. Where the spring V^2 connects with the plate U the connection is liable to become clogged with dust in time, in which case the other line would carry the current until the device could be cleaned, if necessary.

It will be seen that when a key is pressed electrical contact is made, operating the magnet H , lifting its armature, and permitting the corresponding pneumatic J to exhaust, thereby lifting the bar Q and completing the circuit through the conductors N and N' . At the same time the lever L is actuated, permitting the pneumatic a^3 to exhaust, closing the valve a .

A^4 indicates a swell-chest provided with a rail 4 , provided with an electrical conductor-arm 5 . The conductor N is led to a binding

post 6, with which the corresponding contact-arm 5 may make electrical contact when said arm is suitably actuated, as by a pneumatic 7, attached by a connecting-rod 8 with said 5 arm, the contact-arm 5 and binding-post 6 forming a switch mechanism. The arm 5 is connected by a conductor n^2 with a junction-plate P^2 . An electromagnet H^4 may be employed to govern the operation of the pneumatic 7, said latter magnet controlling a valve 11 in a wind-box 12, provided with a pneumatic 13, which operates valves 14, controlling communication from the box 12 through a channel 15 with the pneumatic 7. The 15 magnet H^4 is provided with a conductor n^3 , leading to a junction-plate P^4 , and with a conductor n^4 , leading to a junction-plate P^3 . The junction-plate P^4 is connected by a conductor n^5 with a battery N^7 . Connected with the 20 junction-plate P^3 is a conductor n^6 .

N^8 is a switch connected by a wire n^7 to the battery N^7 to close the circuit between the conductors n^6 and n^7 . W is a coupler to actuate said switch.

25 Z is a chest provided with a channel C^2 , which may lead to a chest similar to the chest B , the communication of the swell-chest Z with the channel C^2 being controlled by valves 1 and 2 upon a stem 3, connected with a pneumatic 9, exhausting through a channel 10.

30 H^5 is an electromagnet governing the passage of wind from the wind-box Z through the channel C^2 to a swell-chest similar to the chest B by means of the valves 1 and 2. The 35 magnet governs the channel 10 by means of a valve 16.

35 P^5 and P^6 denote junction-plates, the magnet H^5 being connected with the plate P^5 by means of a conductor n^8 , the magnet being 40 connected with the plate P^6 by means of a conductor n^9 . The junction-plate P^2 on the chest A^4 is connected with the junction-plate P^6 by a conductor N^9 , and the battery N^6 is connected with the junction-plate P^5 by a conductor N^{10} .

45 The mechanism connected with the wind-box A may be played with one set of keys, and the mechanism connected with the wind-box Z may also be played with the same set of 50 keys when the proper coupler is drawn.

I would have it understood that there may be one or more rails R in the wind-chest A .

The rod v' , passing through the rear end of the key S , may be provided with a button or 55 nut V^5 . The non-conducting strip S' may be supported upon a screw S^2 , passing through the rear end of the key, the screw being adjustable, so as to raise the strip S' to any desired height.

60 The finger r of the rail R , it will be evident, makes contact with the pin q whenever the pneumatic J is actuated, whether the coupler mechanism is off or on. The rubbing contact of these parts r and q when the 65 coupler is off and the keys are played keeps said parts clean. It will be understood that the finger r and the pin q are not in elec-

trical contact or, in other words, in a closed circuit, except when the coupler W is drawn. In addition to the circuit being closed through 70 the plate U and the conductor n^2 and thence, as described, to the battery through the conductor n' the current may also pass through the spring V^2 to the plate V^4 , the spring answering the double purpose of securing 75 the proper tension upon the key and also to carry the current when inserted. This makes doubly sure of having the conductor n' and the plate U in circuit, as already described. By spreading or contracting the spring I am also 80 able to get a lighter or heavier touch of the key, as may be required. Moreover, by screwing up the nut or button V^5 upon the rod V' , I am enabled to regulate the dip of the key to give 85 more or less motion thereto.

I prefer to lead the conductor N' from a junction-plate P^4 , a conductor n^{10} leading from said plate to form contact with the adjacent pin q .

The plate V^3 is employed and located as 90 shown to make the parts more readily accessible should it be desired to take out the spring V^2 and without interfering with the circuit and also to enable me more readily to take out the key. If it should be desired 95 to remove the key, the plate V^3 could be removed and the spring V^2 taken out. Then by dropping the button or nut V^5 the key can be dropped down and lifted off the fulcrum-pin 17 on the rail 18. The rod V' , it will be 100 understood, is used to hold the key in place and is engaged with the rail V .

The electrical circuits may be readily traced. For example, when the strip Q is raised the circuit is closed through the corresponding pin q , the conductor n^{10} , the conductor N' , the conductor n' , the battery N^6 , thence through the conductor N^{10} , through the magnet H^5 , and back on the conductor N^9 , through the arm 5, when in closed circuit, 110 and the conductor N . By striking the key the circuit is closed through the finger t , conductor N^2 , the magnet H , thence back through the battery N^6 , conductor n' , plate V^4 to the plate U .

115 The plates P serve only for a single magnet, while the plates P' and V^4 may carry current for several magnets.

What I claim as my invention is—

1. In an organ, provided with an electro-magnet and with a battery in electrical connection therewith, the combination of a key, a contact-plate upon the upper surface of the key at the inner end thereof electrically connected with said battery, a contact-rail, a contact-finger supported upon said rail adjacent to said contact-plate and normally separated therefrom in electrical connection with said magnet, and a non-conductor upon which said finger may normally rest, said contact-plate 120 recessed at its rear end and provided with a cross-piece u^2 at its rear extremity, and said contact-finger constructed with a rib t' oblique to the cross-piece to form a sliding con-

tact with said cross-piece, said contact-plate forming electrical contact with said finger when the key is depressed.

2. In an organ provided with an electro-magnet and a battery in electrical connection therewith, the combination of a key provided with a contact-plate in electrical connection with said battery, a contact-bar provided with a contact-finger in electrical connection with the magnet, said key provided with a non-conductor upon which the contact-finger may normally rest, said contact-plate forming electrical contact with said contact-finger when the key is depressed.
3. In an organ provided with an electro-magnet and a battery in electrical connection therewith, the combination of a key provided with a contact-plate in electrical connection with said battery, a contact-bar provided with a contact-finger in electrical connection with the magnet, said key provided with a non-conductor upon which the contact-finger may normally rest, a regulating-screw supporting said non-conductor to adjust the position of the non-conductor, said contact-plate forming electrical contact with said contact-finger when the key is depressed.
4. In an organ provided with an electro-magnet and with a battery in electrical connection therewith, the combination of a key provided with a contact-plate in electrical connection with the battery, a contact-bar provided with a contact-finger in electrical connection with the magnet, said contact-plate bifurcated at its rear end and having the bifurcated extremities connected with a metal cross-piece, said contact-finger provided with an angularly-arranged rib, said cross-piece forming a sliding contact with said rib when the key is depressed.
5. In an organ, the combination with a wind-chest having a top board recessed on its upper surface and provided with channels a^2 and a^4 , a recessed bed-plate located in the recess of the top board formed with openings therethrough communicating with the channels a^2 and a^4 respectively, an electromagnet provided with a base-plate located over said recessed bed-plate and forming a chamber therebetween, and an armature located in said chamber to control communication therethrough into the channel a^4 .
6. In an organ, the combination with a wind-chest having a recessed top board provided with channels a^2 and a^4 , a recessed bed-plate formed with an opening therethrough communicating with the channel a^4 , an electro-magnet provided with a base-plate located over said bed-plate and forming a chamber

therebelow, and an armature located in the chamber between said plates to control communication through said opening, said plates constructed with registering orifices through which said plates may be connected with said top board, and said bed-plate constructed with an additional opening through which the channel a^2 communicates into said chamber.

7. In an organ, the combination with a wind-chest provided with a channel communicating therewith, valves to control said communication, a pneumatic to actuate said valves, additional valves to govern the exhaust of said pneumatic, an additional pneumatic, a rail provided with a contact-finger, a contact-bar Q connected with the additional pneumatic and actuated thereby to form electrical contact with said finger, a lever actuated by the additional pneumatic simultaneously with the operation of said contact-bar and connected with the last-named valves, an electromagnet to govern said additional pneumatic, electrical conductors in connection with said contact-finger and other conductors in connection with said magnet, and a battery in circuit with said conductors.

8. In a fresh-wind or pallet box, the combination of a pneumatic, a magnet to control said pneumatic, a contact device actuated by said pneumatic, a conductor leading into said box to form contact with the contact device when the latter device is actuated, and a coupler-actuated switch to control the circuit through said conductor, said contact device contacting with said conductor whether said switch be opened or closed.

9. In an organ mechanism, the combination of a key, an electric circuit, a contact-bar to close the electric circuit when the key is depressed, a spring to exert its tension upon the key and forming a part of the electric circuit, and an additional conductor connecting said key with said circuit.

10. In an organ, the combination of a key provided with a contact-plate, a contact-bar provided with a contact-finger to form electrical contact with said plate when the key is depressed, electrically-connected junction-plates V^3 and V^4 , a conductor connecting the contact-plate with the junction-plate V^3 , and a spring connecting the contact-plate and the junction-plate V^4 .

In testimony whereof I sign this specification in the presence of two witnesses.

WILLIAM B. FLEMING.
